DESIGN FOR A JACKET

Ruth Karplus, Jackson Heights, N. Y., assignor to Mavest Inc., New York, N. Y., a corporation of
New York

Application August 15, 1938, Serial No. 79,337

Term of patent 3½ years

To all whom it may concern:

Be it known that I, Ruth Karplus (assignor to Mavest Inc.), a citizen of Germany, residing at 37-12 87th Street, Jackson Heights, Borough of Queens, city of New York, in the county of New York and State of New York, have invented a new, original, and ornamental Design for a Jacket, of which the following is a specification, reference being had to the accompanying drawing, forming part thereof.

Fig. 1 is a front view of a jacket showing my design; and

Fig. 2 is a similar view of the jacket shown in Fig. 1 showing the lapels in open position.

The back of the jacket is conventionally plain.

I claim:

The ornamental design for a jacket, as shown and described.

RUTH KARPLUS.
